UNITED STATES PATENT OFFICE.

FREDERICK H. GLEASON, OF AUBURN, NEW YORK, ASSIGNOR TO BOWEN PRODUCTS CORPORATION, OF AUBURN, NEW YORK, A CORPORATION OF NEW YORK.

ADJUSTABLE TUBING CLIP.

Application filed July 18, 1923. Serial No. 652,371.

To all whom it may concern:

Be it known that I, FREDERICK H. GLEASON, a citizen of the United States of America, of Auburn, in the county of Cayuga, in the State of New York, have invented new and useful Improvements in Adjustable Tubing Clips, of which the following, taken in connection with the accompanying drawings, is a full, clear, and exact description.

This invention relates to a certain new and useful adjustable tubing clip.

The main object of the invention is to provide a clip which will rigidly hold a tube to any adjacent structural part, said clip being capable of always tightly clamping the tube first and then clamping to the structural part, provision being made in clamping means to accommodate structural parts of various shapes and sizes with the same clip, all constructed and arranged in such a manner that a single bolt or machine screw constitutes adequate means for securely clamping the tube to the clip and the clip to the structural part.

Other objects and advantages relate to the details of form and construction of the clip, all as will more fully appear from the following description, taken in connection with the accompanying drawings, in which:

Figure 1 is a perspective view of a clip of my invention.

Figure 2 is a top plan view of the same as applied in actual use.

Figure 3 is a sectional view on line 3—3, Figure 2.

Figures 4 and 5 are sectional views similar to Figure 3 illustrating the clamp as applied to structural parts of different sizes and shapes.

As illustrated in the drawings, the clip comprises an elongated substantially flat strip of comparatively thin sheet metal sufficiently flexible so as to conform itself to the various shapes of the structural parts about which it is adapted to be clamped. This strip —1— is formed with a series of openings —2—, —3—, —4—, —5— and —6—, altho the number of the openings and the extent of their spaced relation may be varied.

The openings —5— and —6— are adapted to be brought into registration or alignment, as illustrated in the drawings, when the end portion —7— of the strip —1— is returned

bent into substantially parallel relation with the body of the strip —1—, as illustrated in Figure 1.

The return bend of the end portion —7— is effected in such a manner or is thereafter shaped to form a substantially cylindrical or transverse tubular part —8— extending from side to side of the strip —1— and normally having one side open with the end part —7— of the strip —1— spaced some distance from the body of the strip. The cylindrical or tubular part —8— is adapted to receive the tube —9— which may, for illustration, be a portion of a chassis-lubricating system for automobiles or the like when the clip is used for supporting such a system from the structural parts of the chassis.

The tube —9— is placed in the cylindrical part —8— and the bolt or machine screw —10— is passed thru the openings —6— and —5—, and constitutes a means for drawing the end portion —7— into substantial contact with the body of the strip —1— to thereby constrict the cylindrical part —8— so that it tightly engages and substantially encircles the tube —9—. The opposite end of the strip —1— may then be bent around the structural part to which the clip is to be secured in the manner illustrated in Figures 2, 3, 4 and 5 and the end portion of the strip is bent outwardly at substantially right angles to the longitudinal axis of the structural part until the proper one of the openings —2—, —3— or —4— is in substantial alignment with the machine screw —10— so that the screw or bolt —10— will pass through the desired opening and may be threaded into the nut —14— to effect a secure and rigid engagement of the tube —9— with the cylindrical part —8— and a rigid engagement of the structural part —15— with the enclosing portion of the strip —1—.

The lines or marks —11—, —12— and —13— are placed upon the upper surface of the strip —1— and are spaced one-half the width of the machine screw nut —14— from the center of the holes —2—, —3— and —4—, these marks locating the lines upon which the strip is to be bent for the various adjustment holes.

In Figures 2 and 3 the clip acts to clamp the tube —9— to a comparatively small diameter round structural shape —15— and

the clip is bent at substantially right angles on the line —13— and the screw —10— is passed thru the openings —6—, —5— and —4— and threaded into the nut —14— in alignment with said openings to draw the parts to desired position where the tube —9— is tightly clamped within the cylindrical part —8— and the structural part —15— is tightly clamped within the encircling portion of the strip —1—.

In Figures 3 and 4 larger structural parts —16— and —17— respectively are shown, the two parts being of somewhat different form, but in each case of such size that the strip is bent along the line —11— so that the opening —2— is in registration with the openings —6— and —5— for the reception of the machine screw —10—. Because of the spaced relation of the end —7— with respect to the strip —1— in normal form of the clip as manufactured, the first strain of the machine screw —10— will clamp the tube —9— tightly in the cylindrical part —8— and further movement of the screw through nut —14— will then tighten the encircling part of the strip —1— on the structural part as —15—, and the nut —14— is prevented from turning by reason of the fact that the strip —1— was bent on one of the lines —11—, —12— or —13— at substantially a right angle to the body of the strip when the clip was assembled.

The strain exerted on the clamp across the space —18— when the clamp is assembled prevents the machine screw —12— from turning or loosening in nut —13— and always maintains the clamp tight. As before suggested, any strain caused by tightening screw —10— first clamps the tube —9— in the cylindrical part —8— and then tightens the clip on the structural part as —15—.

The construction of this clip provides for assembly on any structural shape within the maximum and minimum scope of the clamp and is an efficient means for positively clamping the tube —9— on any of these shapes.

Altho I have shown and described a specific form and shape of clamp as constituting an embodiment of my invention, it will be obvious that changes may be made in the details of the disclosed form and shape without departing from this invention as set forth in the appended claims.

I claim:

1. A tubing clip comprising a bendable strip of metal having one end portion return bent upon the body of the strip, and connected to the body by a transverse substantially cylindrical portion, said return bent portion formed with an opening and said strip formed with an opening registering with the opening in the return bent portion, and said strip formed near its op-

posite end with a plurality of openings arranged at different distances from the end of the strip.

2. A tubing clip comprising a bendable strip of metal having one end portion return bent upon the body of the strip, and connected to the body by a transverse substantially cylindrical portion, said return bent portion formed with an opening and said strip formed with an opening registering with the opening in the return bent portion, and said strip formed near its opposite end with a plurality of openings arranged at different distances from the end of the strip, and lines extending transversely of the strip between the last-named openings.

3. A tubing clip comprising a bendable strip of metal having one end portion return bent upon the body of the strip and connected to the body by a transverse substantially cylindrical portion, said return bent portion normally spaced from the body of the strip and provided with an opening and said strip formed with an opening registering with the opening in the return bent portion, and said strip formed near its opposite end with a plurality of openings arranged at different distances from the end of the strip.

4. A tubing clip comprising a bendable strip of metal having one end portion return bent upon the body of the strip and connected to the body by a transverse substantially cylindrical portion, said return bent portion spaced from the body of the strip and formed with an opening and said strip formed with an opening registering with the opening in the return bent portion, and said strip formed near its opposite end with a plurality of openings arranged at different distances from the end of the strip and extending substantially parallel with but spaced from the strip.

5. In a device of the character described, the combination with a structural part of a bendable strip of sheet metal bent around said part and having an end portion return bent upon the body of the strip and connected to the strip by a transverse substantially cylindrical part, a tube within said cylindrical part, said return bent portion formed with an opening and said strip formed with an opening near said cylindrical part in alignment with the opening in the return bent part and said strip formed with an opening near its opposite end in substantial alignment with the opening through the return bent portion, and a unitary means extending through all of said openings for clamping the cylindrical part about the tube and for clamping the metallic strip to the structural part.

6. In a device of the character described, the combination with a structural part of a

bendable strip of sheet metal bent around said part and having an end portion return bent upon the body of the strip and connected to the strip by a transverse substantially cylindrical part, a tube within said cylindrical part, said return bent portion formed with an opening and said strip formed with an opening near said cylindrical part in alignment with the opening 5 in the return bent part, and said strip formed with an opening near its opposite end in substantial alignment with the opening through the return bent portion, and a machine screw extended thru all of said 10 aligned openings, and a nut mounted on said screw for clamping the cylindrical part to the tube and for clamping the metallic strip to the structural part.

15 7. In a device of the character described, 20 the combination with a structural part of a

metallic strip bent around said part and having end parts projecting outwardly therefrom at substantially a right angle to the longitudinal axis of the structural part, one of said end parts having a return bent portion lying in substantial parallelism with the part and connected to the part by a transverse substantially cylindrical portion, said end parts provided with registering openings and said return bent portion provided 25 with an opening registering with the openings in the end parts, and a bolt extended thru said openings and a nut mounted on said bolt.

30

In witness whereof I have hereunto set my hand this 10th day of July, 1923.

FREDERICK H. GLEASON.
